UNITED STATES PATENT OFFICE.

EDWARD T. DYSON AND HARRY S. BULLEN, OF OAKLAND, CALIFORNIA.

SHIPPING-CASE.

1,225,705.

Specification of Letters Patent.

Patented May 8, 1917.

Application filed May 5, 1915. Serial No. 25,961.

To all whom it may concern:

Be it known that we, EDWARD T. DYSON and HARRY S. BULLEN, citizens of the United States, residing at Oakland, in the county of 5 Alameda and State of California, have invented certain new and useful Improvements in Shipping-Cases, of which the following is a specification.

This invention relates to improvements in 10 containers and more particularly to a device for shipping berries or small fruit by express or parcel post, the principal object of our invention being to provide a package containing several trays all of 15 which are made from corrugated straw board, thereby making a shipping container which is light in weight, yet strong and rigid.

Another object of our invention is to construct trays for said container that one is 20 supported on another, the upper tray being held against horizontal movement with respect to the lower tray, and being supported such a distance from the lower tray as not 25 to crush the contents thereof.

Another object of our invention is to form 30 this tray of a single piece of straw board and in such a manner that the same may be readily manufactured by automatic machinery.

Another object of our invention is to 35 form the outer covering of said trays of a single piece of corrugated straw board of such form that the bottom and top thereof have double thicknesses, thereby serving as 40 cushions; to provide proper air passages and ventilating openings, which align with the openings of the tray that a good circulation of air is secured therethrough.

With these and other objects in view our 45 invention consists in the novel construction, combination and arrangement of parts as herein described and more specifically pointed out in the appended claim.

Reference being had to the accompanying 50 drawing forming a part of this specification,

Figure 1 is a view in perspective of our improved container having one corner 55 broken away to show the arrangement of trays therein.

Fig. 2 is a view in end elevation of a number of trays nested one on the other.

Fig. 3 is a view in plan of the blank from 55 which the said trays are formed.

Fig. 4 is a view in plan of the blank from which the outer cover is formed.

Fig. 5 is a view in section on the line 5—5, Fig. 2.

Referring to corresponding parts by the 60 same numerals of reference, 1 denotes the outer cover comprising the top 2, the sides 3, bottom 4 and ends 5, the said sides being provided with ventilating openings 6 and the ends with ventilating openings 7. The 65 blank from which this container is formed is illustrated in Fig. 4 wherein is seen that the ends 5 are formed continuously with the sides 3, one-half of each end being formed on each of the sides and the openings 7 being formed one-half in each half of the end. The top and bottom 1 and 4 are provided with the extension flaps 8, these 70 flaps being folded back on the line 9 to the position shown in dotted lines in Fig. 4. 75 This provides the top and bottom adjacent the ends with two thicknesses of material, which assists in cushioning any shock which the contents may be subjected to by reason of the box being dropped or otherwise 80 roughly handled. The container is folded along the lines shown by dashes and the half ends 5 are of such length that they abut together forming a smooth outside surface.

The trays denoted in general by 10 comprise a bottom portion 11, side 12 and the ends 13. In forming the blank for this tray the sides 12 are provided with tabs 14, which when the ends 13 are bent up fold around the ends and are fastened by means 85 of a wire staple as shown at 15'. The ends are provided with upstanding ears 15 and in the base along the edge adjacent the ends are provided openings 16 so arranged that when nesting the ears 15 of the trays below 90 enter this opening and so prevent horizontal shifting of one box with respect to the other, the weight of the upper box resting 95 on the shoulder 18 of the box below.

In use the trays are formed by folding up 100 the ends along the dotted lines, bending the sides and folding the tabs 14 around the ends and fastening by means of staples 15 as already explained. When the trays are 105 filled they are seated on the bottom 4 of the outer case. Then the sides 3 are bent upwardly around the tray and the ends 5 swung into position. The top 1 is then turned down and the various joining abutments of edges sealed by means of a piece 110

of adhesive tape 19. It will be noted that a slot, as indicated at 18', is then formed between each of the trays while in the end of each is an opening 17, which enables the 5 fingers to be inserted to lift one tray from the other. The openings 6 in the side of the container aline with a slot 18 and the openings 7 of the end aline with the opening 17, thus securing a free passage of air into 10 the various trays.

What we claim as new and wish to cover by Letters Patent is:—

A shipping case comprising an outer container having top and bottom closures and

ventilating openings in the sides and ends 15 thereof, a plurality of nested trays adapted to be held in said container, shoulders formed on each of said trays adapted to support the superimposed trays a fixed distance therefrom, the space between said 20 trays alining with the ventilating openings in said container.

In testimony whereof we affix our signatures in presence of a witness.

EDWARD T. DYSON.
HARRY S. BULLEN.

Witness:

RUTH M. OYARZO.
